OIL-BURNER CONSTRUCTION

George Irving Carter, Teaneck, N. J., assignor to
 General Oil Heating Corporation, West New
 York, N. J., a corporation of New Jersey

Application August 3, 1940, Serial No. 350,392

16 Claims.

(Cl. 158—28)

This invention relates to oil-burner construction.

Oil-burning, as, for instance, by means of the spray nozzle in domestic installations, includes the factor of economy of space, as well as convenience of access, as, for instance, for adjustment or repair. It is an object of the invention to provide a compactly constructed oil-burner in which parts requiring adjustment are easily and conveniently accessible for adjustment, even while the burner is in active operation, firing the furnace, and without danger to the adjuster.

An oil-burner construction, commonly used in domestic installations, is the so-called "gun" type. Oil, atomized by means of a nozzle, is burned with air brought into immediate association with the atomized oil. Many different attempts have been made to obtain proper association of the atomized oil and the air in order to make combustion as complete as possible before the hot gases derived from the burning oil pass to the surfaces of the furnace at which the heat is to be absorbed. One method found successful, especially in furnaces having small combustion chambers, is that in which turbulence in the air for combustion is induced by causing the air to follow a helical path at least at the time of its association with the atomized oil to be burned. It is an object of the invention to provide compact apparatus for producing turbulence in the flow of air with relation to atomized oil by causing the air to flow along substantially helical paths relative to the atomizing means.

Where an ordinary furnace assembly is located in a domestic heating installation, space is generally at a premium. This generally becomes acute when access both to boiler and to oil-burner must be considered. It is an object of the invention to provide apparatus in which the extent of the oil-burner outside the furnace is reduced so as to facilitate assembly of the burner with the furnace, as well as access to the burner for repair or adjustment.

The oil-burner used here to illustrate certain features of the invention is of a type which has become known as the "twin." A pair of air-ducts lead to a single blast or fire tube. The air-ducts cooperate with the blast tube in such manner that blasts following helical paths form within the blast tube, and effect cyclonic flow of air past a nozzle which is atomizing the fuel. It is an object of the invention to arrange ducts and blast tube in such manner that adjustments, after erection of the oil-burner, may be

made easily and without necessity for dismantling the installed burner, or any substantial part thereof.

This result may be effected by leading the air-ducts vertically downwardly to the blast tube, which may be disposed in a direction transversely of the extent of the air-ducts, and then mounting the fans for the air-blower and the motor for driving the fans immediately above the blast tube and not in line or in the same plane with the blast tube. In such an assembly, it is possible to associate these rapidly moving parts so that vibration will be eliminated substantially completely as an item in producing noise when the burner is in operation. For such purpose, resilient mounting of the motor and the fans as well as the oil-pump, to dampen out or absorb such vibrations completely within the burner casing, is utilized.

Access to the atomizing nozzle and to the electrodes is of material operating importance. It is an object of the invention to provide a means for assembly of electrodes and nozzle in an oil-burner by which the ready removal of electrodes and atomizing nozzle may be effected, as, for instance, for any repairs, changes or adjustments, without affecting the installation, and then the electrodes and atomizing nozzle may as readily be replaced in the assembly.

It is an object of the invention to provide apparatus in which the transformer which produces the high tension current necessary for the electrodes of a twin blast tube burner is mounted to guard certain of the operating parts of the burner. It is an object of the invention to mount the transformer so that, when it is moved into position to make certain of the burner parts accessible, the transformer is disconnected automatically from the electrodes.

An air-director may be used in conjunction with the blast tube to control the shaping of the flame. It is an object of the invention to provide an air-director, adjustable with relation to the oil-spray nozzle and other parts of the blast tube, wherein such adjustment may be made from a position outside of the furnace, and even while the burner is in operation.

It is an object of the invention to mount fans, motor and oil-pump, all on a single shaft, and to support all from simple bearings associated with the blower housings.

Other objects of this invention will be set forth hereinafter, or will be apparent from the description and the drawings in which is illustrated

an embodiment of apparatus exemplifying the invention.

The invention, however, is not intended to be restricted to any particular construction, or to any particular arrangement of parts, or to any particular application of any such construction or arrangement of parts, or to any specific method of operation, or to any of various details thereof, herein shown and described, as the same may be modified in various particulars or be applied in many varied relations without departing from the spirit and scope of the claimed invention, of which the exemplifying embodiment, herein shown and described, is intended only to be illustrative, but not to show all the various forms and modifications in which the invention might be embodied.

On the drawings in which the same reference characters refer to the same parts throughout:

Fig. 1 is an elevational perspective view of an oil-burner construction, embodying the invention;

Fig. 2 is an elevational perspective view of the oil-burner construction shown in Fig. 1, as seen from the rear or adjusting end of the construction, one of the feet being broken away to illustrate details of the construction;

Fig. 3 is a view similar to Fig. 2, the transformer housing being swung to open position, the valve assembly being removed, and the blower casing covers being shown lifted out of secured position;

Fig. 4 is a perspective view of the assembly of sleeve, electrodes and nozzle;

Fig. 5 is a plan view of the oil-burner construction of Fig. 1, certain of the parts being shown in dotted, or dot-and-dash lines;

Fig. 6 is a vertical cross-sectional view taken transversely of the oil-burner construction of Fig. 1, as seen from the line 6—6, certain of the parts being shown in elevation, the spider for supporting the electrodes and nozzle being shown in dot-and-dash lines;

Fig. 7 is a vertical cross-sectional view substantially on the line 7—7 of Fig. 6, the oil pump being shown as if the front plate of the housing were removed, certain of the parts being shown in elevation; and

Fig. 8 is a detail cross-sectional view substantially on the line 8—8 of Fig. 6, parts of the blower casing being broken away in section.

In the oil-burner construction 10 shown on the drawings, blast ducts 12 and 14 lead to a "gun" or blast tube 16 from blower wells 18 and 20. Blast tube 16 ducts 12 and 14, and wells 18 and 20 may be defined in a single casting 22. The leg 24 of a T-shaped member 26 may be secured immediately at the bottom of the casting. The transverse arms 28 of member 26 may have a flange 30 to be engaged against and to be secured to outside wall 32 of the ducts and a flange extension 34 of the duct walls.

At the ends of leg 24 and arms 28 are screw-threaded openings 36 to receive threaded bolts 38. These bolts extend into threaded openings 40 in feet 42. Lock nuts 44 may cooperate with bolts 38, the threaded openings, and the feet to lock the feet in any position into which the feet may be adjusted. Since three of these feet are provided, the level of the apparatus may be adjusted accurately.

Flange 30 may have an arcuate section 46 to cooperate with a cylindrical flange 48, which forms the rearmost portion of tube 16. Tube 16, in its forward section 50, is a substantially cylindrical member having a cylindrical bore 52. Into this bore, at the forward section of the tube, may

be fitted air-deflector 54. This air-deflector takes the form of a sleeve having a passage 56 through a frusto-conical section 58 and a cylindrical section 60. Section 60 has a smooth outer wall to fit substantially snugly within bore 52. A rod 62 may have a threaded end 64 turned upwardly and secured in a hole 66 in section 60. The rod extends downwardly into a passage 68 formed in a projection 70 from the cylindrical formation of casting 22 at tube 16. A spring 72 encircles the rod and engages against a stop pin 74 on the rod, and also against a part of wall 32. The rod has a threaded end extended through an opening 76 in wall 32, and receives a wing-nut 78. Thus, as the wing-nut is turned, air-deflector 54 will move with relation to front end 50 of the blast tube.

Immediately within tube 16 in front of wall 32 are ports 82 and 84 in walls 86 of tube 16. These ports, diametrically opposed, open into the passages of ducts 12 and 14. In the instance shown, duct 12 leads to port 82, which is at the topmost portion of tube 16, while duct 14 leads to port 84, which is at the bottommost portion of tube 16. Substantial portions of walls 86 between ports 82 and 84 are faced to provide a seat 88 for receiving a sleeve 90. Sleeve 90 includes a cylindrical section 92 having ports 94 and 96 formed therein. The extent of these ports may be substantially the same as the extents of ports 82 and 84. Sleeve 90 is positioned within seat 88 and immediately in cooperation with ports 82 and 84 so that ports 84 and 96 respectively may be brought into cooperation with ports 82 and 84.

As sleeve 90 is rotated within seat 88, ports 94 and 96, cooperating with ports 82 and 84, are effective to graduate the amount of opening of ports 82 and 84 from a maximum to a minimum. By rotating the sleeve in the direction indicated by the arrow in Fig. 6, portions of ports 82 and 84 at the extreme outermost parts of ducts 12 and 14 will be uncovered, while the other parts towards the walls of ducts 12 and 14 substantially radially of the axis of tube 16 will be covered. It is thus possible to maintain the character of blasts issuing from ducts 12 and 14 into tube 16 at all times as tangential, that is, immediately in contact with inner wall 86 of the tube.

Seat 88 includes a shoulder 98 against which forward edge 100 of sleeve 90 may abut to retain the sleeve in position within the tube. In order to retain the sleeve within the tube, a removable wall 102 may be secured in position against flange 48 by suitable securing devices such as screws 104 passed through lugs 106, and engaging threaded openings in bosses 108 associated with flange 48. Sleeve 90 has an inturned flange 110 for reception around a frusto-conical projection 112 from wall 102. This interfitting relationship between flange 110 and projection 112 further functions as a bearing for the sleeve. A screw 114, engaged in flange 110, may be extended through a slot 116 in wall 102 to be accessible at the rear end of the burner. By loosening screw 114, sleeve 90 may be rotated within the tube without removing the sleeve or any of the other parts from the assembly, but merely by pushing on the screw. When the sleeve has been adjusted into the desired position, screw 114 is tightened against wall 102 at slot 116, and the sleeve is thus fixed in its adjusted position.

Ducts 12 and 14, in addition to horizontal portions 118 and 120, turn upwardly into vertical ducts 122 and 124. Vertical ducts 122 and 124 are spaced substantially an equal distance be-

yond the center-line of tube 16, and are enlarged into wells 18 and 20 at substantially equal positions above the center-line of the tube. Wells 18 and 20 are half sections of blower casings 128 and 128. The other half sections of these blower casings are provided by covers 130 and 132. The covers are complementary sections, which, together with wells 18 and 20, form casings 128 and 128, which cooperate with squirrel-cage fans 134 and 136 at the opposed ends of a shaft 138. The covers are retained in position by suitable securing means, such as screws 140 passed through lugs 142 on the covers and lugs 144 on the wells. The fans, driven by suitable means, produce equally effective blasts through ducts 12 and 14, so that equally effective blasts will issue past ports 94 and 96 of sleeve 80.

A pair of openings 148 are formed through conical projection 112, and receive insulators 148 of electrodes 150. Opening 152, formed through the center of projection 112, receives oil-tube 154; the coupling of tube 154 in opening 152 may be produced by any suitable means, as, for instance, by a threaded connection. At the free end of tube 154, a nozzle 156 is positioned. A spider 158, disposed to contact with the walls of tube 16, may receive tube 154 through a central passage, and thus serve to locate tube 154 and nozzle 156 centrally of tube 16. A clamp 160 may engage a projection 162 at the inner face of conical projection 112, and may be shaped for reception over portions of insulators 148. Thus, when clamp 160 is tightened by suitable means such as screws, both electrodes will be locked in position against separation, and in the position in which they may have been adjusted prior to assembly in tube 16. Thus electrodes 150 and nozzle 156 may be adjusted externally of the burner, and then, merely by sliding them through the rear opening in flange 48, and by engaging proper screws 164 with lugs 166 and bosses 168, the entire assembly, including sleeve 80, may be located in the burner as a unit.

At the outer face of projection 112, opening 152 receives the end connection of a flexible tube 164 which leads to the outlet 166 from oil-pump 168. Oil-pump 168 is mounted and fixed in a casing 170, which, in turn, is fixed to and thus made substantially an integral part of casing 172 of motor 174. End bearings 176 for shaft 136, which extends between fans 134 and 136 and through motor 174 and oil-pump 168, are fixedly related to the motor and the oil-pump by being made substantially integral with casings 170 and 172. A ring 178 of cushioning material has an opening 180 through which a bearing 176 is received. The outside face of the ring is received between a pair of straps 182 and 184, forming a clamp 186, the straps being shaped to provide a substantially cylindrical cavity to receive the ring. One strap 182 may have toes 188 resting upon arms 190 of the other strap 184 and secured thereto by any suitable means such as screws 192. Arms 190 may extend beyond toes 188 to have rests 194 formed at the ends. Rests 194 may be U-shaped in cross-section. Arms 190 bridge openings 196 in inner walls 198 of wells 18 and 20, and rest on top edges 200 of walls 198, with rests 194 seating over the edges and restraining clamp 186 against lateral displacement. It is thus made possible, by taking off covers 130 and 132 and disconnecting flexible tube 164 and a flexible tube 202 to be described, to remove the entire motor-oil-pump-fan assembly from the apparatus as a unit. Openings 196 cooper-

ate with openings 203 in covers 130 and 132 to form air inlets for the blower casings.

A bracket 204 on wall 32 may provide for connection to the source of oil. To a threaded opening through this bracket, tube 202 will be connected, although it may be desirable to have tube 202 free. Tube 202 is connected to inlet 206 to the oil-pump on casing 170. Within casing 170 is also located pressure relief valve 208 and strainer 210, all of which may be of conventional construction, and require no specific description here. Outlet 166 from the strainer provides a connection for flexible tube 164.

Extending rearwardly from projection 112 are electrode ends 214, which are formed as contacts. A wall 216 may be mounted pivotally on lugs 218 formed on wall 32. This wall may be formed so as to provide an inner chamber 220 within which are positioned terminals 222. These are the terminals of a transformer 224 which is mounted on the outside face of wall 216. A connection box 226 located on wall 32 provides the necessary cables 228 and 230 for electrical connection to motor 174 and transformer 224. Terminals 222 include a pair of spring fingers 232 so located that, when wall 216 is swung to bring its leg 234 into abutment with wall 32, spring fingers 232 will contact ends 214 of the electrodes. Also, when wall 216 is in this position, access to screw 114 and to wing-nut 78 is prevented, or hindered. Thus, it becomes necessary, in order to make any adjustments on the burner, to cut off the ignition mechanism of the burner. The adjustments may be made while the burner is in operation, and after ignition has been completed, but not during the first stages of commencement of a run. After ignition has been effected, wall 216 may be moved clear of the adjusting means and so that ends 214 no longer are in contact with terminals 222. Then sleeve 80 or air deflector 54 may be adjusted. Wall 216 may be retained against wall 32 by engagement of a screw 236 through leg 234 with wall 32.

Many other changes could be effected in the particular apparatus designed, and in methods of operation and use set forth, and in specific details thereof, without substantially departing from the invention intended to be defined in the claims, the specific description being merely of an exemplifying embodiment in accordance with the statutes.

What is claimed as new and useful is:

1. In oil-burner construction, a blast tube having a substantially open firing end, the other end of the tube being closed, the tube having a laterally opening port, means communicating with the tube through said port for producing a flow of air in the tube from the port to the firing end, electrodes supported in the tube and extending from the tube through the closed end, and a transformer mounted on the tube for movement into and out of electrical circuit-making relation to the extending electrodes.

2. In oil-burner construction, a blast tube having an open end in the direction of movement of the blast therethrough, means for initiating a blast of air, an end wall for closing the other end of the tube, means assembled with the end wall for directing the initiated blast into a substantially cyclonic path from the closed end to the open end of the tube, and means accessible on the outside face of the end wall for adjusting the directing means.

3. In oil-burner construction, a blast tube having an open end for directing the blast from the

tube into a furnace, the other end of the tube being closed, communicating means forming a junction with a lateral wall of the tube adjacent the closed end, means for initiating a blast of air in the communicating means, means at the junction of the communicating means and the tube for controlling the initiated blast from the communicating means to cause it to maintain a substantially cyclonic path within the tube, and means extending outside the closed end for adjusting the controlling means.

4. In oil-burner construction, a blast tube having an open end for directing the blast from the tube into a furnace, the other end of the tube being closed, communicating means adjacent the closed end and leading into the tube through a lateral wall thereof, means for initiating a blast of air in the communicating means, a sleeve mounted in the tube at the closed end, the sleeve having a port for cooperation with the communicating means to direct the blast into a substantially cyclonic path within the tube, and means extending through the closed end for adjusting the sleeve.

5. In oil-burner construction, a blast tube having an open end for directing the blast from the tube into a furnace, the other end of the tube being closed by a wall, a pair of ducts adjacent but forwardly from the end wall, the ducts opening into the tube through a lateral wall thereof and extending laterally and upwardly away from the tube to form substantially a U with the tube, means for initiating blasts of air in the ducts, the communication between the tube and the ducts including means to discharge the initiated blasts into substantially interlaced cyclonic paths within the tube, and means extending through the end wall for adjusting the discharging means.

6. In oil-burner construction, a blast tube having an open end for directing the blast from the tube into a furnace, the other end of the tube being closed by a wall, a pair of ducts adjacent but forwardly from the end wall, the ducts opening into the tube through a lateral wall thereof and extending laterally and upwardly away from the tube to form substantially a U with the tube, and means for initiating blasts of air in the ducts, the communication between the tube and the ducts including means to discharge the initiated blasts into substantially interlaced cyclonic paths within the tube.

7. In combination, a pair of blower wells positioned in spaced apart relationship, a pair of ducts leading downwardly from the wells and towards each other, a tube having ports in its lateral walls, the ducts having communication with the tube through the ports, and means in the tube and cooperating with the ports for controlling simultaneously the effective opening of the ports, the tube extending substantially horizontally away from the location of the communication with the ducts.

8. In combination, a pair of blower wells positioned in spaced apart relationship, a pair of ducts extending substantially vertically downwardly from the wells and then towards each other, a tube having means for closing one end thereof, and having ports opening through its lateral walls, the ducts having communication with the tube through the ports, and means cooperating with the ports to control simultaneously the effective opening of the ports, the controlling means being capable of manipulation through the closed end of the tube, simultane-

ously driven means in the wells for producing blasts of air in the ducts, and means in the tube beyond the controlling means for supplying fuel in dispersed form.

9. In combination, a pair of blower wells positioned in space apart relationship, a pair of ducts extending substantially vertically downwardly from the wells and then towards each other, a tube having means for closing one end thereof, and having ports opening through its lateral walls, the ducts having communication with the tube through the ports, a sleeve rotatable in the tube for adjusting simultaneously the effective opening of the ports, the sleeve being immediately contiguous to and being capable of manipulation through the closed end of the tube, simultaneously driven means in the wells for producing blasts of air in the ducts, and means in the tube beyond the controlling means for supplying fuel in dispersed form.

10. In oil-burner construction, a blast tube having an open end and a wall closing the other end, electrodes extending into the blast tube towards the open end from the end wall and projecting outside the blast tube through the end wall, air-supply ducts immediately at the end wall leading away from the lateral walls of the blast tube, means in the blast tube for controlling air-flow from the ducts into the tube, the controlling means having manipulating means extending through the end wall, a transformer for the electrodes, the transformer being mounted on the blast tube to move towards and away from the end wall, and means on the transformer and the electrode projections for breaking the circuit between transformer and electrodes when the transformer is moved away from the end wall to make the manipulating means accessible.

11. In oil-burner construction, a blast tube having an open end and a wall closing the other end, electrodes extending into the blast tube towards the open end from the end wall and projecting outside the blast tube through the end wall, air-directing means in the blast tube, the air-directing means being movable in the tube, means extending from the air-directing means and beyond the end wall for effecting adjusting movement of the air-directing means, a transformer for the electrodes, the transformer being mounted on the blast tube to move towards and away from the end wall, and means on the transformer and the electrode projections for breaking the circuit between transformer and electrodes when the transformer is moved away from the end wall to make the adjusting-movement-effecting means accessible.

12. In oil-burner construction, a pair of blower wells positioned in spaced apart relationship and having walls facing each other, a blast tube, ducts leading downwardly from the wells and uniting with the blast tube, a single shaft extending into both wells, fans on the ends of the shaft, a motor on the shaft between the facing walls, the motor having a casing, bearings for the shaft, and means for engaging the facing walls to retain the bearings fixedly related and retained against rotation relative to the casing.

13. In oil-burner construction, a pair of blower wells positioned in spaced apart relationship and having walls facing each other, cover sections for assembly on the top edges of the walls of the wells to form blower casings, a blast tube, ducts leading downwardly from the wells and connected with and supported by the blast tube, a single shaft extending into both blower casings,

fans on the ends of the shaft, a motor on the shaft between the facing walls, the motor having a casing, bearings for the shaft, the bearings being fixedly related to the motor casing, and a suspension resting upon the top edges of said facing walls for supporting the bearings and retaining them against rotation.

14. In oil-burner construction, a pair of blower wells having facing walls positioned in spaced apart relationship, a blast tube, ducts leading downwardly from the wells and connected with and supported by the blast tube, a single shaft extending into both wells, fans on the ends of the shaft, a motor on the shaft, the motor having a casing, an oil-pump for the oil-burner, the shaft extending through the oil-pump, the oil-pump being secured against rotation relative to the motor casing, means for delivering oil from the oil-pump in mixing relation to the air blast of the blast tube, bearings for the shaft, the bearings being fixedly related to the casing, the bearings being engaged by the facing walls of the wells and thereby restrained against rotation.

15. In oil-burner construction, a pair of blower wells positioned in spaced apart relationship and having walls facing each other, a blast tube, ducts leading downwardly from the wells and connected

5 with and supported by the blast tube, a single shaft extending into both wells, fans on the ends of the shaft, a motor on the shaft between the facing walls, a casing for the motor, bearings for the shaft fixedly related to the casing, and resilient means secured to said facing walls and engaging the bearings to prevent rotation of the bearings and to cushion the support of the bearings on the walls.

10 16. In oil-burner construction, a pair of blower wells positioned in spaced apart relationship and having walls facing each other, cover sections for assembly on the top edges of the walls of the wells to form blower casings, a blast tube, ducts leading downwardly from the wells and connected with and supported by the blast tube, a single shaft extending into both blower casings, fans on the ends of the shaft, a motor on the shaft between the facing walls, the motor having a casing, bearings for the shaft fixedly related to the motor casing, and resilient means secured to the top edges of said facing walls and engaging the bearings to prevent rotation of the bearings and to cushion the support of the bearings on the walls.

20 25 GEORGE IRVING CARTER.
